Augustus B. Stoughton
ATTORNEY.

UNITED STATES PATENT OFFICE

LUTHER D. LOVEKIN, OF VILLA NOVA, PENNSYLVANIA

VALVE DEVICE FOR CONNECTION TO A HOT WATER SUPPLY

Application filed May 1, 1931. Serial No. 534,167.

The principal object of the present invention is to provide a device of the character referred to with an improved type of valve; another object is to simplify and improve the construction, arrangement and operation of the various parts; another object is to facilitate the operation of servicing or readjusting the valve device; and another object is to provide a convenient, accurate and reliable valve device constructed either to respond to temperature change alone or to either or both temperature change and pressure change due to change of temperature of the water.

Other objects of the invention will appear from the following description at the end of which the invention will be claimed, but, generally stated, the invention may be said to comprise a valve device adapted for connection with a hot water supply and comprising a two-part valve casing of which one part is provided with a stem guide and with a cylindrical chamber and of which the other part is provided with inlet and outlet openings and with a raised valve seat between said openings, a piston movable in said cylindrical chamber and provided at one end with a fiber face adapted for cooperation with said raised seat and at the other end with a cavity, a fusible metal body arranged in the cavity and accessible upon separation of the two parts of the casing, a stem movable through the stem guide opening and having at one end a tapered head seated on said body, and screw means accessible from the outside of the device and arranged for operation at the other end of the stem.

The invention also comprises the improvements to be presently described and finally claimed.

In the following description reference will be made to the accompanying drawing forming part hereof and in which

Figure 1 is a central vertical sectional view of a device embodying features of the inven-

tion and responsive to both temperature and pressure changes of water, and

Fig. 2 is a similar view of a valve device responsive to temperature changes only.

Referring to the drawing and more particularly to Fig. 2, 1 and 2 indicate the parts of a two-part valve casing. The part 1 is provided with an inlet opening 3 and an outlet opening 4, and with a raised valve seat 5 arranged between said openings. The part 2 is provided with a stem guide 6 and with a cylindrical chamber or cylinder 7. 8 is a piston movable in the cylindrical chamber 7 and it is provided at one end with a head having a fiber face 9 adapted for cooperation with the raised seat 5. At the other end of the piston there is a cavity 10. 11 is a fusible body arranged in the cavity and it is accessible upon separation of the parts 1 and 2 of the casing. 12 is a stem movable through the stem guide opening 6, and it is provided with a tapered head 13 seated on the body 11. There are screw means accessible from the outside of the device and they are arranged to operate at the end of the stem opposite to the head 13. As shown in Fig. 2, these means comprise a threaded portion 14 and the hand piece 15. The operation may be described as follows:

The inlet opening 3 is connected with a supply of hot water and as the temperature of the water rises, heat is conducted through the piston 8 to the fusible body 11 which being softened by the heat permits the piston 8 to recede or rise into the cylindrical chamber 7, lifting the valve 9 from its seat 5 and embedding the end of the head 13 in the body 11. As the valve 9 rises, hot water passes it and escapes through the outlet opening 4, for example to a waste connection. Thereafter and when the temperature of the water has been lowered and the body 11 has sufficiently solidified, it is possible to close the valve 9 on its seat 5 by turning the handle 15 and by that simple operation the valve device has been

reset or readjusted. However, in the operation of the device the body 11 may, by softening under heat, become displaced from between the end of the head and the bottom of the cavity 10. In that case the part 2 of the valve is detached from the part 1 and the connections to the inlet 3 and outlet 4 need not be disturbed. The piston 8 is withdrawn carrying with it the deformed body 11 which is removed and replaced by a new body 11. When the head 13 is of tapered form, the removal of the deformed body is facilitated because it can be readily separated from the head 13. Under normal conditions water at the inlet 3 is entirely excluded from the body 11, which is desirable as the alloys of which the bodies are made are affected by water, and under no circumstances does sufficient water ever contact with the body 11 to substantially affect it. The piston 8 and its cylinder serve the purpose of sufficiently excluding water from the body 11.

The construction and mode of operation of the valve device illustrated in Fig. 1 are as has been above described in connection with Fig. 2 except as follows:

The valve device shown in Fig. 1 is responsive to change in temperature of the water and also to change in pressure of the water induced by change in temperature of the water. There is a bonnet 16 detachably secured to the part 2 of the valve casing and it, together with the part 2, provides a housing 17 for a spring 18 which presses on the stem 12 and also on the support 19. A set screw 20 extending through the top of the bonnet presses on the support 19, and the set screw 20 may be adjusted to change the pressure of the spring 18. 21 is a cap mounted on the top of the bonnet and it encloses the set screw. 22 is a basket or cup in which is placed the body 11, and it facilitates the removal of the body after it has been softened and has again set or become solid. As rise in pressure of the water at the inlet 3, insufficient to raise the temperature of the water sufficiently to soften the body 11, causes the piston 8 to rise and clear the valve 9 from the seat 3 against the pressure of the spring 18 acting through the stem 12 and through the body 11. A sufficient rise in temperature of the water softens the body 11 so that it is deformed and the piston 8 may rise without compressing the spring 18. It is an advantage in servicing the valve device that the parts 2 and 16 are removed as a unitary structure and therefore the setting of the tension of the spring may not be accidentally changed.

It will be obvious to those skilled in the art to which the invention relates that modifications may be made in details of construction and arrangement and matters of mere form without departing from the spirit of the invention which is not limited to such matters

or otherwise than the prior art and the appended claims may require.

I claim:

1. A valve device adapted for connection with a hot water supply and comprising a two part valve casing of which one part is provided with a stem guide opening and with a cylindrical chamber and of which the other part is provided with inlet and outlet openings and with a raised valve seat between said openings, a piston movable in said cylindrical chamber and provided at one end with a head having a fiber face adapted for cooperation with said raised seat and at the other end with a cavity, a fusible metal body arranged in the cavity and accessible upon separation of the two parts of the casing, a stem movable through the stem guide opening and having at one end a tapered head seated on said body, and screw means accessible from the outside of the device and arranged for operation at the other end of the stem for holding said head seated on said body.

2. A valve device adapted for connection with a hot water supply and comprising a two-part valve casing of which one part is provided with a cylindrical chamber and of which the other part is provided with inlet and outlet openings and with a valve seat between said openings, a piston movable in said cylindrical chamber and provided with a head at one end and having a fiber face adapted for cooperation with said seat, a fusible metal body arranged at the end of the piston opposite the fiber face and accessible upon separation of the two parts of the casing, and a stem held seated on said body.

3. A valve device adapted for connection with a hot water supply comprising a two part valve casing of which one part is provided with a stem guide and with a cylindrical chamber and of which the other part is provided with inlet and outlet openings and with a valve seat between said openings, a piston movable in said cylindrical chamber and provided at one end with a head having a face adapted for cooperation with the valve seat, a fusible metal body arranged at the end of the piston opposite said face, a stem movable through the stem guide opening, a bonnet detachably connected with the first mentioned part of the casing, a spring housed in the bonnet and last mentioned part of the casing and arranged for operation on the stem, and a set screw for adjusting the tension of the spring.

4. A valve device adapted for connection with a hot water supply comprising a two part valve casing of which one part is provided with a stem guide and with a cylindrical chamber and of which the other part is provided with inlet and outlet openings and with a valve seat between said openings, a piston movable in said cylindrical chamber and provided at one end with a head having a

face adapted for cooperation with the valve seat, a fusible metal body arranged at the end of the piston opposite said face, a stem movable through the stem guide opening, a bonnet detachably connected with the first mentioned part of the casing, a spring housed in the bonnet and first mentioned part of the casing and arranged for operation on the stem, a set screw for adjusting the tension of the spring, and a detachable cap mounted on the bonnet and enclosing the set screw.
